CHARLES C. KUNDE, OF NEW YORK, N. Y., ASSIGNOR TO JULIUS ADERER INC., OF NEW YORK, N. Y., A CORPORATION OF NEW YORK

CLASP AND CLASP SUPPORTED DENTAL RESTORATION

Application filed May 31, 1930. Serial No. 457,906.

This invention relates to restorations supported from abutment teeth by clasps and to the clasps used for that purpose. The object of the invention is to supply a clasp of 5 novel construction possessing great resiliency and adapted to be associated with a restoration in such a manner as to produce improved results. Clasps for such purposes are intended to partially embrace abutment teeth 10 and to support removable bridgework or partial dentures. The clasps in themselves are ready-made articles of merchandise which are customarily associated with the restoration by dentists or dental technicians familiar 15 with the proper manner in which such clasps should be associated or attached to the restoration in order to produce the desired results.

The invention is illustrated in the accompanying drawings in which Fig. 1 is a front view of a typical restoration with the clasps in position for use, but before the final placing of the artificial teeth. Fig. 2 is a view of the device illustrated in Fig. 1 taken from 25 the under side of the saddle. Fig. 3 is a view similar to Fig. 1 with the artificial teeth in place. Fig. 4 is an inverted view of Fig. 3. Fig. 5 illustrates the structure of Fig. 3 when associated with the abutment teeth. Fig. 6 30 is an inverted view of Fig. 5. Fig. 7 is an enlarged sectional view taken on line 7-7 of Fig. 5. Fig. 8 is a similar enlarged sectional view taken on line 8-8 of Fig. 5. Fig. 9 is an enlarged detailed face view of the clasp as 35 associated with the occlusal rest. Fig. 10 is a side view of Fig. 9. Fig. 11 is a sectional plan view taken on line 11-11 of Fig. 9, and Fig. 12 is an enlarged cross-sectional detail view taken on line 12-12 of Fig. 11.

40 In the drawings Figs. 5 and 6 show a typical example of a complete restoration in place. This type of restoration comprises, as shown in Figs. 1 to 4, the saddle 1, the posts 2, the occlusal rests 3, the clasps 4, and the 45 artificial teeth 2a, the artificial teeth being placed upon and cemented to the posts 2. The clasp 4, as more clearly shown in Figs. 9 to 12, is preferably a continuous resilient wire member of acid-resisting metal or alloy 50 bent over near the central portion to form the

vertical arms 5, the two free ends of the bent wire being thereupon first bent outwardly and then inwardly at approximately right angles from the vertical arms 5 to form the relatively semi-circular clasp sections 6. 55 Preferably the vertical arms 5 are circular in cross-section while the clasp sections 6 are flattened on their inner surfaces as illustrated in Fig. 12, although the clasp can, of course, be constructed in either the round, 60 half-round, oval, or bevelled wire or any combination of any such shapes. The clasp sections 6 are furthermore, in the preferred embodiment of the invention, shaped so that they extend into slightly different planes. 65 Thus, as shown in Fig. 9, the terminal portion 7, which is adapted to be positioned on the lingual side of the tooth, is closer to the occlusal rest 3 than is the opposed terminal portion 8 which is adapted to occupy a position on the buccal side of the tooth. The vertical or tortional arms 5, on the other hand, may be longer on the lingual than on the buccal, depending on the angle of the abutment tooth to be clasped. In other 75 words, in the manufacture of the clasps, as ready-made articles of commerce, they will be made with tortional arms of the same lengths and of different lengths and of unequal lengths, so that the dental technician 80 can select the one which is appropriate to the particular condition of his subject.

In making a denture such for example as shown in Fig. 1, a dentist usually makes a plaster impression and from that plaster impression the laboratory which he uses shapes the saddle 1 to conform closely to the tissue as indicated in Fig. 7. The pins 2 are incorporated in the saddle structure and after the restoration has been finally fitted, the artificial teeth 5 are cemented upon the pins 2. In completing the restoration the occlusal rest 3 which usually constitutes an integral extension of the saddle portion of the restoration is formed and shaped to conform 90 with the adjacent abutment teeth 9, so that ultimately the relation between the saddle 1, the occlusal rest 3, and the abutment teeth 9 and the gum or tissue 95 100

will represent as near a perfect and exact fit as the dentist can possibly obtain. When this perfection of fit and conformity has been determined, the clasp member 4 is soldered 5 or cast into the restoration so as to be supported therefrom in the region of the bent-over portion of the vertical arms 5 of the clasp as indicated at 3a in Figs. 7 and 10, so that the major portion of the vertical arms 10 and the horizontal arms are capable of moving with respect to the restoration except at the point where the clasp is attached beneath the occlusal rest. It will be observed that in such a construction, as the clasping sections 6 15 are spread apart in passing over the sides of the abutment teeth, they will have the benefit not only of their own resiliency, but of the torsional resiliency of the vertical arms 5. The result of this combination of resiliency 20 and torsional movements is to increase the over-all resiliency capacity of the clasp and to furnish a tight gripping contact under both torsional and resiliency effects against the outer faces of the abutment teeth. In order 25 to achieve this result, the permanent union between the clasp and the restoration is, as stated, restricted to the upper portion of the clasp, so as to leave the vertical or torsion arms capable of spring movement as 30 well as torsional movement, also giving the horizontal terminal clasping members 6 and 7, and 6 and 8, respectively, an opportunity of moving torsionally.

The torsion arms 5 of the clasp are positioned on the approximal sides of the supporting teeth. The extension clasping sections embrace said abutment teeth, both at the buccal and the lingual cervical margins of the teeth. This feature is a result of the 40 structure of the new clasp and is the consequence of its powerful resiliency. In prior clasps the resiliency was insufficient to enable the clasping members to be positioned closer to the margins of the teeth than the junction 45 of the cervical third of the tooth, i.e. closely below the widest part of the teeth. In such prior structures, if the clasping arms were moved further toward the gum line, the arms would not have sufficient resiliency to close 50 upon the tooth and to hold the appliance in proper position. With my new clasp, however, due to its capacity to permit proper flexure under spring and torsional influences, it is possible to bring the free arms of the 55 clasp close to the tissue as indicated in Fig. 5. This results in a material reduction of conspicuousness as well as a more secure and reliable anchorage.

Another feature involved in the use of the 60 new clasp is that it permits the entire vertical section of the clasp, as well as of the metal which terminates in the occlusal rest 3, to be completely hidden from view between the natural abutment teeth and the adjacent 65 artificial teeth. As indicated in Fig. 7, the

artificial tooth 2a is ground on one of its approximal sides to form the recess 10 capable of receiving the metal from which the occlusal rest 3 projects, as well as that portion of the clasp which lies between the artificial tooth and the abutment tooth. This recess must be of such dimensions as to allow for the movement of the clasp when the torsion arms 5 are spread apart or subjected to torsional strains. This means that care should be taken to allow sufficient free space not only laterally of the arms 5 (as shown in Fig. 7) but also at the corner portion 11 of the recess 10 so as to avoid contact or binding at those corners. When the clasp is thus seated in the recess 10, the whole of it except the clasping sections 6 (as shown in Figs. 5 and 6) will be completely invisible while the relation between the natural supporting tooth and the adjacent artificial tooth can be that of an actual contact at their approximal sides. The result of such an arrangement is to render the removable appliance very much less conspicuous and better able to reproduce the natural conditions. 90 The reason for the special shape given to the end sections 7 and 8 (Fig. 9) of the clasp member is to make them more readily conform to the angles of the teeth. As indicated in Fig. 8, the natural abutment tooth 9 extends somewhat at an angle from the tissue so that in order to obtain a proper grip at the buccal and lingual cervical margins of the tooth, respectively, the gripping ends 7 and 8 of the clasp are required to be seated 100 in slightly different planes.

The wire of which the clasp is made may be round in cross-section throughout. In the preferred construction, however, a round wire of about 18 or 19 gauge is used and the free ends thereof are placed in a machine which flattens the two ends to the necessary extent indicated in Figs. 9 and 12, so that the extension arms are about 14 or 15 gauge. The thus formed resiliency wire is then bent at its center to form the vertical arms 5, while the flattened portions are then bent at approximately right angles to the vertical arms 5 and are then curved to approximate semi-circles with the flat faces 12 facing each other. The object of these flat faces is, of course, to afford a better contacting grip against the abutment teeth than is possible if the wire at this part of the appliance were round.

Among the leading advantages of the new structure is its markedly increased resiliency which is obtained without sacrifice of strength. In prior types of clasps, due to their lack of adequate resiliency, the supporting or abutment tooth is placed under strain and is moved according to the tension of the appliance as a whole. In the new clasp the resiliency is such that the appliance adjusts 130

itself to the teeth and not the teeth to the appliance.

Due to the construction of the new clasp the life of the metal is extended because the

5 strains are taken up in the flexibility of the structure and the tendency to break or to become distorted is reduced to a minimum.

When the new clasp is used, there is considerably less strain on the natural teeth.

10 The new clasp, also, due to its peculiar resiliency, provides a better anchor than prior clasps. In inserting and removing the appliance, there is less friction on the natural teeth than in the case of less resiliency clasps.

15 The free ends of the new clasp can be more readily and accurately adjusted to the shape of the natural teeth than was heretofore possible with prior ready-made clasps. This is, in part, due to the relatively small dimensions of the clasp wire which lend themselves

20 to easy manipulations to assure close conforming contact, as well as to the great resiliency of the clasp which assures maintenance of close conforming contact after it is once established.

25 In attaching the new clasp at its upper portion in the space below the occlusal rest, it is not necessary to make any special or adjusted fit as between the clasp and the denture. The 30 clasp can be soldered in and the free ends then shaped by tools to fit accurately around the abutment teeth.

Numerous other advantages result from the use and application of the new clasp.

35 It is understood that in the appended claims the invention is intended to be covered with due regard to equivalent or modified structures incorporating the essence of the novel features of my invention.

40 I claim:

1. A clasp adapted to support a dental restoration from an abutment tooth, composed of resilient metal comprising two elongated approximately parallel closely adjacent vertical arms having free ends, said free ends being bent first outwardly and then inwardly from each of the vertical arms at approximately right angles thereto, said clasp on attachment to a restoration being held only at those portions of the vertical arms which are most remote from the free ends whereby, when the free ends are spread apart, they will be placed under resilient as well as tortional influence.

45 2. A clasp of the character set forth in claim 1 in which the resilient metal of which the clasp is composed is constituted of a continuous wire bent upon itself to form the two vertical arms.

50 3. A clasp of the character set forth in claim 1 in which the vertical arms are substantially round in cross-section, while the free end sections are provided with substantial vertical flattened faces.

55 4. A clasp of the character set forth in

claim 1 in which the free ends terminate at a distance from each other approximating the lateral extent of the approximal surface of two contiguous teeth.

5. A restoration comprising a saddle, an 70 occlusal rest supported by the saddle, a clasp of the character defined in claim 1, and means by which the upper end only of the vertical arms of the clasp are attached below the occlusal rest.

6. A restoration comprising a saddle, an 75 occlusal rest supported by the saddle, a clasp of the character defined in claim 1, and means which attach the upper end only of the vertical arms of the clasp below the occlusal 80 rest and position the free ends of the clasp at the cervical margin of the abutment tooth.

7. A restoration comprising a saddle, an 85 occlusal rest supported by the saddle, a clasp of the character defined in claim 1, an artificial tooth, a recess in the artificial tooth of sufficient dimensions to receive the vertical arms of the clasp and to permit movement thereof within said recess and means for attaching the clasp at the upper end of the 90 vertical arms so as to permit the same, while firmly attached to the structure, to have lateral and tortional movement in the recess as the free ends of the clasp are spread apart.

In witness whereof I have hereunto set my 95 hand.

CHARLES C. KUNDE.
